UNITED STATES PATENT OFFICE.

NATE H. ROBERTS, OF INDIANAPOLIS, INDIANA, ASSIGNOR TO THE E. C. ATKINS & COMPANY, OF SAME PLACE.

BUCKSAW-FRAME.

SPECIFICATION forming part of Letters Patent No. 424,999, dated April 8, 1890.

Application filed June 24, 1889. Serial No. 315,318. (No model.)

To all whom it may concern:

Be it known that I, NATE H. ROBERTS, a citizen of the United States, residing at Indianapolis, in the county of Marion and State of Indiana, have invented certain new and useful Improvements in Bucksaw-Frames, of which the following is a specification.

My invention consists in a peculiar arrangement of tension-rods by which the frame of a bucksaw is held to the desired tension without braces other than the ordinary central cross-bar, and this in a very simple and effective manner.

Referring to the accompanying drawings, which are made a part hereof, and on which similar letters of reference indicate similar parts, Figure 1 is a side elevation of a bucksaw-frame having or embodying my said invention; Fig. 2, a detail sectional view on an enlarged scale, showing the upper end of the rod and that portion of the frame through which it passes; and Fig. 3, a similar view of the other end of the rod and adjacent parts of the frame, showing the angle to which the hooked ends of the rods are preferably bent.

In said drawings, the portions marked A represent the ends of the bucksaw-frame, B the saw, and C the rods.

The ends A are similar to those of an ordinary bucksaw, as is also the cross-bar A', which extends between them, except that said cross-bar has holes extending into it at an angle, as will be presently described, to receive the hooked ends of the rods, and the ends of said end pieces are also so bored to receive the other ends of said rods. Bushings or sleeves a' may be inserted in these holes, if desired, in order to protect them from wearing.

The rods C are two plain light screw-rods, having thumb-screws c upon their outer ends, and having their inner ends c' hooked, as shown, at an angle somewhat more acute than a right angle. The object of this is to prevent the hooks from drawing out of the holes in the cross-bar A', the tendency rather being to draw the hooks farther into the hole with the increasing pressure occasioned by the tightening of the thumb-screws. A link

or ring c² surrounds these rods where they cross, thus preventing them from springing apart sidewise. This construction is very effective in operation, and can be easily adjusted so as to throw the frame into any position desired, the variation in position being secured by loosening one thumb-screw and tightening the other, as will be readily understood.

Having thus fully described my said invention, what I claim as new, and desire to secure by Letters Patent, is—

1. The combination, with the end pieces and central bar of a bucksaw-frame, of tension-rods C, crossing each other and engaging with the frame-work, said tension-rods being provided with hooks upon one end and thumb-screws upon the other, whereby said engagement is effected, substantially as set forth.

2. The combination, with the end pieces and central bar of a bucksaw-frame, of tension-rods, the ends of which engage with said frame, one end of each of said rods being hooked for the purposes of said engagement, the hooked portion being at an angle slightly more acute than the right angle with the body of the rod, and said central bar being provided with holes to receive said hooked portions, substantially as shown and described.

3. The combination of the end pieces and central bar of a bucksaw-frame and tension-rods crossing each other and engaging with said bar and said end pieces, and a ring or a link surrounding said rods where they cross, substantially as shown and described.

4. The combination of the end pieces A, the bar A', and rods C, said bar A' having holes to receive the ends of said rods, with bushings or sleeves therein, substantially as set forth.

In witness whereof I have hereunto set my hand and seal, at Indianapolis, Indiana, this 17th day of June, A. D. 1889.

NATE H. ROBERTS. [L. S.]
